UNITED STATES PATENT OFFICE.

WILLIAM C. HACKMAN, OF MILWAUKEE, WISCONSIN.

RAIL JOINT.

Application filed November 23, 1925. Serial No. 70,861.

The invention relates to rail joints.

In usual practice the ends of adjacent rails are connected by fish-plates which permit relative movement of the ends of the rails, with the result that the ends of the rails are flattened down at the joint and become battered and uneven causing shocks to be transmitted to the cars passing over the uneven rails which produce wear on the rolling stock, and in the case of passenger trains causes discomfort to the passengers because of the jolting effects. The object of this invention is to provide a rail joint in which the fish-plates are firmly interlocked with the rails by wedge means associated with the fish-plates and the adjacent ends of the rail, and a further object of the invention is to maintain a substantially even pressure on the wedge means at all times so as to take up any slack that may occur at the joint.

The invention further consists in the several features hereinafter set forth and more particularly defined by claims at the conclusion hereof.

In the drawings, Fig. 1 is a plan view of a rail joint embodying the invention;

Fig. 2 is a section taken on the line 2-2 of Fig. 1;

Fig. 3 is an elevation view of one side of the joint;

Fig. 4 is an elevation view of the other side of the joint.

In the drawings the numeral 5 designates a pair of adjoining rails, 6 fish-plates, 7 a wedge, 8 wedge-locking springs, and 9 and 10 spring-locking wedges.

The fish-plates 6 are of special construction in that in addition to their angled portions 11 and 12, designed to respectively engage the web 13 and base flange 14 of the rails, they are each provided with a depending flange 15 having a slot 16. A wedge-plate 17 has an outer depending flange 18, an intermediate flange 19 and an upwardly projecting flange 20, and is designed to be passed through the slots 16 of the fish-plates to assume the position shown in Fig. 2. The wedge 7 is driven in between the under sides 21 of both the rails and the plate 17 and by its wedging action presses upwardly on the rails and downwardly on the plate 17 which in turn presses or pulls downwardly on the flanges 15, with the result that the portion 12 of the fish-plates is firmly held against the adjacent rails, which cannot

move relative to each other because of the vice-like grip of the ends of the rails between the wedge 7 and the fish-plates. The fish-plates 6, in addition, have their angled portions 11 secured to the web of the rail by the bolts 22 and said plates preferably have longitudinally extending recesses 23 adjacent the bolts to facilitate a fit against the rail.

Any suitable means may be used for exerting pressure between the wedge 7 and the plate 17 to hold the wedge 7 in place, but I prefer to provide means which will insure a constant predetermined or known pressure acting on said wedge. For this purpose the wedges 9 and 10 and the springs 8 are used. The back face of the wedge 7 is provided with spring-seat projections 24; the wedge 9 with similar projections 25; and the wedge 10 with locking projections 26 adapted to enter into holes 27 in the flange 20.

It will be noted that the plate 17 and the wedge 7 are of sufficient width to extend beneath parts of both of the rail ends.

With this construction the fish-plates 6 are first attached to the rail by the bolts 22 and the plate 17 with the wedge 7 loose thereon is moved in so as to engage the depending flanges 15 of the fish plates; the wedge 7 is then pushed forwardly after which the springs 8 with the wedge piece 9 are put on the plate 17; the wedge 10 is then driven between the wedge 9 and the projecting flange 20 on the plate 17, thereby forcing the wedge 9 inwardly and compressing the springs 8 and finally becoming locked when the pins 36 register with the holes 27, at which time the springs 8 have been given a predetermined tension which they constantly exert against the wedge 7 and hold it firmly in position and thus prevent any slack occurring between the parts of the joint. The tension of the springs 8 is great enough so as to exceed that component of the bearing pressure, exerted at any one time upon the rails by the rolling stock tending to lessen the wedge connection.

I desire it to be understood that this invention is not to be limited to any specific form or arrangement of parts except in so far as such limitations are specified in the claims or necessitated by the prior art.

What I claim as my invention is:

1. In a rail joint, the combination with the adjoining rail ends, of fish-plates, wedge

means engageable with parts of said fish-plates and with the adjacent ends of the rails to firmly hold the fish-plates and rail ends together, and spring means for exerting a constant predetermined tension on said wedge means.

5. In a rail joint, the combination with the adjoining rail ends, of fish-plates secured to the adjacent ends of the rails and having depending flanges, of wedge means co-operating with said flanges to firmly clamp the fish-plates to the base flanges of the rail, and spring means for exerting a constant predetermined tension on said wedge means.

15. 3. In a rail joint, the combination of a pair of fish-plates secured to the ends of adjoining rails and provided with depending slotted flanges, a wedge plate carried by said flanges, a wedge disposed between said plate and the bottom sides of the rails at the joint, and spring means for maintaining said wedge in operative position.

4. In a rail joint, the combination of a pair of fish-plates secured to the ends of adjoining rails and provided with depending slotted flanges, a wedge plate carried by said flanges, a wedge disposed between said

plate and the bottom sides of the rails at the joint, a spring, and spring tensioning wedges interposed between said wedge and 30 said wedge plate.

5. In a rail joint, the combination of a pair of fish-plates secured to the ends of adjoining rails and provided with depending slotted flanges, a wedge plate carried by said flanges, a wedge disposed between said plate and the bottom sides of the rails at the joint, a spring, and spring tensioning wedges interposed between said wedge and 35 said tensioning wedge plate, one of said wedges having interlocking engagement with said wedge plate.

6. In a rail joint, the combination with the adjoining rail ends, of fish-plates, wedge means engageable with parts of said fish-plates and with the adjacent ends of the rails to hold the fish-plates and rail ends together, and spring means exerting a tension on said wedge means in excess of that component of the bearing pressure, exerted 45 upon the rails by the rolling stock, tending to loosen said wedge means.

In testimony whereof, I affix my signature,
WILLIAM C. HACKMAN.
